(57) **CLAIM**

We claim the ornamental design for a carton, as shown and described.

DESCRIPTION

FIG. 1 is a top perspective view of a a carton of the present invention;

FIG. 2 is a front view thereof;

FIG. 3 is a rear view thereof;

FIG. 4 is a first side view thereof, wherein the second side view is a mirror image thereof;

FIG. 5 is a top view;

FIG. 6 is a bottom view;

FIG. 7 is a top perspective view of a of a carton of the present invention shown in an alternate condition of use with the lid removed;

FIG. 8 is a front view thereof;

FIG. 9 is a rear view thereof;

FIG. 10 is a first side view thereof, wherein the second side view is a mirror image thereof;

FIG. 11 is a top view thereof; and,

FIG. 12 is a bottom view thereof.
